DESIGN FOR A CASING FOR A CORN POPPING MACHINE

Herbert B. Tyler, Evanston, Ill.

Application June 19, 1936, Serial No. 63,377

Term of patent 7 years

To all whom it may concern:

Be it known that I, Herbert B. Tyler, a citizen of the United States and a resident of Evanston, in the county of Cook and State of Illinois, have invented a new, original, and ornamental Design for a Casing for a Corn Popping Machine, of which the following is a specification, reference being had to the accompanying drawing, forming a part thereof.

In the drawing:

Figure 1 is a perspective view of the casing for a corn popping machine showing my design, and

Figure 2 is a top plan view of the same.

I claim:

The ornamental design for a casing for a corn popping machine as shown.

HERBERT B. TYLER.
